UNITED STATES PATENT OFFICE.

EUGÈNE SCHNEIDER, OF LA CREUSOT, FRANCE.

SUBMERGING-RUDDER FOR SUBMARINES.

1,246,475.

Specification of Letters Patent. Patented Nov. 13, 1917.

Application filed December 9, 1916. Serial No. 136,117.

To all whom it may concern:

Be it known that I, EUGÈNE SCHNEIDER, a citizen of the French Republic, residing at Le Creusot, France, have invented a new 5 and useful Improvement in Submerging-Rudders for Submarines, which is fully set forth in the following specification.

For the purpose of causing the submerging rudders of submarines to disappear or 10 be retracted during the periods in which they are not required to operate, and thus diminishing as far as possible the resistance offered by them to the progress of the vessel, it has been proposed to provide hinged rudders capable of being folded flat against the 15 side of the hull, and it has also been proposed to use non-pivoted rudders adapted to be retracted wholly or partly into the interior of the hull, that is to say, rudders 20 whereof the blade has a fixed inclination relatively to the vessel, the variations of its action for the purpose of submerging being produced in this case by causing the blade to project more or less from its containing 25 recess in the vessel.

The former of those two ways of diminishing the resistance of the rudder in its inoperative position, has the result that the rudder is not sufficiently protected in its inoperative 30 position, and more particularly the rigidity of the fixing of the rudder blade upon the rudder shank is diminished. The second manner of retracting the rudder has the drawback of rendering the submerging 35 operation too slow.

The present invention has now for its object to provide an improved apparatus which will do away with the drawbacks of both the two methods above referred to. 40 According to this invention the rudders which are capable of being retracted into a recess in the interior of the hull of the vessel, are rendered capable of pivoting, that is to say, of operating by rotation, after 45 their protrusion from the said recess. For this purpose the rudder blade is mounted on a rudder shank which can be kept permanently retracted, and on which the rudder blade is adapted to slide for the purposes 50 of being protruded and retracted. The rotation of the rudder shank carries around with it the sliding rudder blade and thus allows of rotating the latter for steering purposes as desired as soon as it has been 55 moved out into its position of complete protrusion.

The longitudinal movements of the rudder blade sliding along its rotatable shank, for the purpose of protruding and retracting the rudder blade, may of course be produced by mechanical power or by hand through suitable gearing. The said movements may also be produced by means of hydraulic or pneumatic mechanism, for instance by employing a telescopic rudder shank one member 60 of which would constitute the rudder shank proper, while the other member would be fixed to the rudder blade, or a piston might be employed that is fixed to the rudder shank and is movable in a sleeve formed 65 on the rudder blade.

Two embodiments of this invention are illustrated by way of example in the accompanying drawings:—

Figures 1 to 4 illustrate one embodiment. 75

Fig. 1 is a half vertical cross section of a submarine taken along the axis of the submerging rudders, which latter are constructed according to this invention.

Figs. 2 and 3 are vertical cross sections respectively on the lines II—II and III—III of Fig. 1. 80

Fig. 4 is a half plan of a rudder of which the sliding blade is shown in full lines in its retracted position, while the dot and dash 85 lines show it in its protruded position wherein it can be rotated for steering purposes.

Figs. 5 and 6 show the second embodiment of the invention.

Fig. 5 is a half vertical cross section of 90 a submarine taken along the axis of the shank of the submerging rudders.

Fig. 6 is a vertical cross section on the line VI—VI of Fig. 5.

Referring first to the example shown in 95 Figs. 1 to 4, the blade A of the submerging rudder engages by means of a sleeve a^3 on the rudder shank B on which it rests with a bearing part a provided with two collars a^1 — a^2 . This bearing part is mounted in a bearing C which is capable of moving transversely of the submarine, in guides c^1 — c^2 fixed to the walls D^1 of a recess 100 formed in the hull D of the submarine.

The movement of the rudder blade for the purpose of protruding or retracting it, may be produced for example by means of a screw spindle c^3 operated from the interior of the vessel as hereinafter stated. This screw is adapted to rotate without longitudinal motion in a bearing c^4 fixed to the wall D^1 . 110

In the retracting movement of the rudder

der, the bearing C which has a boss C¹ engaging like a nut on the screw c², carries with it the rudder blade A from its external position shown in dot and dash lines, into 5 its internal position shown in full lines in Fig. 1.

The sliding movement of the rudder blade on the rudder shank B without rotation, is effected by means of a feather key b carried 10 by the latter, and engaging in a groove a⁴ extending along the entire length of the sleeve a³.

The key b and the groove a⁴ assure also that the rudder shank shall carry around 15 with it the rudder blade when the latter is in its external position.

In its inward movement the rudder blade enters between the guides c¹ and c², into the recess that is formed by the walls D¹ and the 20 hull of the submarine.

In the example shown in Figs. 1, 2, 3 and 4, the recess for the rudder blade is assumed to be so constructed that its greatest dimension is horizontal.

25 In the example shown in Figs. 5 and 6 which relates to a submarine of the same type, the recess for the rudder blade has its greatest dimension vertical. Consequently it is necessary before retracting the rudder 30 blade, to bring it into a vertical position by means of its shank.

Whatever arrangement is adopted, the recess for the rudder blade is formed by suitable deformations of the plating of the hull 35 of the submarine and of partial partitions. In the figures the submarine is assumed to be of the type having a double hull with external ballast tanks.

40 The rudder shank B and the screw spindle c³ for actuating the bearing C, extend through suitable stuffing boxes b¹ and c⁵ into the inner hull of the submarine. Of course only that part of the screw spindle c³ should be screw-threaded which is outside 45 the said hull.

The rudder shank may be actuated in the usual manner, for instance by means of a toothed sector E and a tangential worm F and power or hand gear. The rotation of 50 the screw spindle c³ for actuating the bearing C may likewise be produced by any suitable means.

Instead of a solid rudder shank B along which the rudder blade A is adapted to slide by means of a sleeve a³ for the purpose of protruding and retracting the rudder blade, it is to be understood that the inverse arrangement may be employed, namely, a hollow rudder shank in which a solid axial member formed in one piece with or fixed 55 to the rudder blade is guided and by which it can be rotated.

What I claim is:—

1. In a submarine having a rudder-receiving recess in its hull, a rotatable rudder shank mounted therein, a rudder blade provided with a sleeve having a splined engagement with said shank, and means for sliding said sleeve on its shank to move said blade in and out of said recess for steering 70 purposes.

2. In a submarine having a rudder-receiving recess in its hull, a rotatable rudder shank mounted in said recess, a rudder blade provided with a sleeve having a splined engagement with said shank, a non-rotatable bearing for said sleeve movable therewith in said recess, and means engaging said bearing for sliding said sleeve on said shank to move said blade in and out of said recess 75 for steering purposes.

3. In a submarine having a rudder-receiving recess in its hull, a rotatable rudder shank mounted in said recess, a rudder blade provided with a sleeve having a splined engagement with said shank, a non-rotatable bearing for said sleeve movable therewith in said recess, and a blade-positioning spindle having threaded engagement with said bearing.

4. In a submarine provided with a rudder-receiving recess, a rotatable rudder shank therein and a rudder slideable in respect to such shank and rotatable therewith, means for moving said rudder in and out of said recess, and means for rotating said rudder in its extended position.

In testimony whereof I have signed this specification in the presence of two subscribing witnesses.

EUGÈNE SCHNEIDER.
